UNITED STATES PATENT OFFICE.

OSCAR ROESEN, DECEASED, LATE OF NEW YORK, N. Y.; BY ISABELLA ROESEN, EXECUTRIX, OF BROOKLYN, NEW YORK; SAID OSCAR ROESEN ASSIGNOR TO R. HOE & CO., OF NEW YORK, N. Y., A CORPORATION OF NEW YORK.

STAPLING AND FOLDING MECHANISM.

Original application filed April 14, 1920, Serial No. 373,687. Divided and this application filed November 28, 1923. Serial No. 677,420.

To all whom it may concern:

Be it known that OSCAR ROESEN, deceased, late a citizen of the United States, and residing in New York city, county of Kings, and State of New York, did, in his lifetime, invent certain new and useful Improvements in Stapling and Folding Mechanisms, of which the following is a specification.

This application is a division of application Serial No. 373,687, and the invention of this application relates to certain improvements in stapling and stitching mechanisms combined with a folding mechanism particularly adapted for use with printing machines.

In printing machines, and particularly rotary printing machines, the products may be produced with the columns running around the printing cylinder, or running transversely across, or parallel with the axis of the printing cylinder, depending on the product desired. This causes the fold line to extend transversely to the product path or longitudinally thereto, and these products are folded usually on the staple line. When products of this class are to be stapled and folded therefore, either the product has to be reversed or turned, or separate stapling mechanism must be employed, both of which involve difficulties and expense in construction.

It is the especial object of the present invention to produce a stapling mechanism which may be operated to insert a staple or a line of staples in a product either transversely to the run or path of the product as it is fed to the staple or longitudinally of the run of the product, so that a product may be stapled either transversely or longitudinally of its run, this stapling mechanism being combined with folding mechanism, this folding mechanism being preferably capacitated to fold the product either longitudinally of its run or transversely thereto.

A further object of the invention is to produce such a mechanism in combination with means for forwarding a web or associated webs from a printing machine, cutting the web into sheets and collecting, stapling, and folding the products obtained therefrom.

The invention consists in certain novel parts, arrangements, and combinations, which will now be fully described in con-

nection with the accompanying drawings and then pointed out in the claims hereunto annexed.

In these drawings—

Figure 1 is a diagrammatic side elevation, partly broken away, of the improved stapling and folding mechanism shown as employed at the folding end of a printing machine, the stapling mechanism being shown as positioned to insert a line of staples longitudinally of the path or run of the product.

Figure 2 is a side elevation, partly broken away and partly in section, showing in detail the stapling mechanism illustrated in Fig. 1, the parts being in the position they occupy when stapling longitudinally of the run of the product.

Figure 3 is a side elevation, partly broken away and partly in section, of the construction shown in Fig. 2, the stapling mechanism being shown turned at right angles to the position shown in Fig. 2, and in the position the parts occupy when stapled transversely of the run of the product.

Figure 4 is a side view of the construction shown in Fig. 3, the view being taken in the direction of arrow 4 of that figure.

Figure 5 is a detail plan view partly in section taken on line 5—5 of Figure 3, showing the staple clinching mechanism and the registering devices for registering the product and the operating mechanism therefor.

Figure 6 is a detail view partly broken away and partly in section taken on line 6—6 of Figure 5, illustrating one of the registering devices and the mechanism for operating it.

Referring now to these drawings, the stapling mechanism is shown in connection with the folder end of a printing machine, one printing couple of which is diagrammatically illustrated as including a form cylinder F and an impression cylinder I. The product to be stapled may be either an associated or collected product as it comes from the machine or it may be a web which is cut into sheets and the sheets associated or collected for stapling. In the particular mechanism illustrated there is shown a web W which is cut into sheets by a pair of cutting cylinders 1, 2 suitably supported in side frames 3 of the machine, these cut-

ting cylinders being provided with the usual knives 4 and cutting woods 5, the web being forwarded to the cutting cylinders by the usual forwarding rollers 6. Where, as in the machine illustrated, a single or associated web or webs is cut into sheets, these sheets are directed by guides 7 to the usual collecting cylinder 8, this cylinder 8 being suitably mounted in the frame 3, and provided with sheet taking devices as grippers 9. From the cylinder 8 the product is forwarded to the stapling mechanism. As shown it is taken by a suitable sheet taking device as jaws 10 on a cylinder 11 suitably mounted in the side frames from which it is delivered to upper and lower tapes 12, 13. The product is carried by these tapes through the stapling mechanism and to and through the folding mechanism to the final delivery.

These tapes may be supported and driven in any suitable manner. The upper tapes 12 are or may be driven from a roll 14 driven from the cylinder 11 before referred to, and passing over suitable tension rolls 15 and guide roll 16. The lower tapes 13 are driven from the cylinder 11, passing over this cylinder and being held in proper position by tension roll 17 and guide roll 18.

In machines embodying the invention there is provided a stapling mechanism to which the product is forwarded which is so constructed that it may be positioned to insert a line of staples longitudinally of the run of the product or transversely thereto, depending on the character of fold the final product is to have, and this stapling mechanism is so designed that it may be readily placed in either position without altering or requiring any changes in the other mechanisms of the machine with which it is to be used except the rethreading of the tapes. The specific construction of this stapling mechanism and the means for mounting it

so that it may be moved into required position may be widely varied. In the best constructions, however, this stapling mechanism will be mounted in a frame which may be swung from one position to a position at right angles thereto, and this frame will carry the means for forming and inserting staples and for positioning the product with respect to the stapling mechanism in either position. In the particular construction illustrated there are provided four uprights, 19, 19', 20, 20' (see Figs. 2, 3). These uprights, at their upper ends, support a fixed frame 21 and their lower ends rise from a bed or base 22 rigidly supported in the side frames 3 of the machine before referred to. Mounted so as to have a rotary or turning movement, between the frames 21, 22, is supported what will be termed a carrying frame indicated generally by the numeral 23, which frame carries and supports

the stapling and registering mechanisms. This frame includes top and bottom members 223, 224 and side members 225, and is mounted pivotally in upper and lower bearings (see Fig. 4) marked 24, 25. In machines embodying the invention this frame is mounted so that it can be given a swinging or turning movement on its pivots and so that this movement can be given the frame without necessitating any changes or adjustments in the mechanisms for inserting the staples and positioning the product in proper relation to the stapling mechanism, this movement being a movement of 90 degrees. In the particular construction illustrated the lower fixed frame 22 is provided with a hollow hub 26 which forms an inner bearing for the lower frame pivot 25 before referred to. This hub forms an outer bearing on which rotates a miter gear 28 having upper and lower driving faces 28, 29. The lower driving face 29 engages with a miter gear 30 on a short shaft 31 suitably journaled in the machine frame, through which shaft the miter is driven, this miter in turn driving the stapling mechanism through connections hereinafter described. This short shaft 31 (see Fig. 1) is driven in any suitable manner. In the particular construction shown (see Fig. 1) this shaft at one end has a miter gear 32 which meshes with a miter gear 33 on a shaft 34, this shaft being provided with a spur gear 35 meshing with a spur gear 36 on a shaft 37, this shaft 37 being driven through a suitable train of gears, one of which, 38, is shown, from the main power shaft 39 of the machine.

The means for effecting the rotation of the frame 23 may be somewhat varied. In the particular construction illustrated this is manually effected. The pivot 25 (see Fig. 4) before referred to is extended below the frame 22 and on its lower end has keyed thereto a worm wheel 40. This worm wheel is arranged to engage with a worm (see Fig. 3) 41 on a short operating shaft 42, the end of which is squared as shown at 43 to permit the use of a tool for rotating it, though it may be rotated in any desired manner. By the rotation of this shaft the carrying frame and the mechanism carried thereby for operating the staple inserting devices may be given a 90 degree movement thereby bringing the staple inserting devices into position to insert the staples either transversely or longitudinally of the product and this movement is such that none of the operating parts of the mechanism are affected or require any adjustment for the different staple inserting positions, except the silencing of one of the operating connections between the operating cams and the staple inserting mechanism, as more fully hereinafter referred to.

In certain constructions it may be desirable that the product be stapled on the run; that is, the stapling mechanism is given a movement corresponding to the speed of the product so that the staples are inserted in the moving product, and machines constructed in accordance with the invention may be provided with the devices for effecting this. While the particular construction may be varied, this construction will be such that the stapling devices may be given this travelling movement in either of the stapling positions. In the particular construction illustrated (see Fig. 3) the carrier frame 23 before referred to, is provided with an inner frame which has a to and fro movement relatively to frame 23 in two opposite directions. This frame is generally marked 400 and is shown as comprising a top 44, bottom 45, and slide members 46. The upper and lower members of this inner frame 44, 45 are dove-tailed, as indicated at 47 (Fig. 3) to slide on guides 48 formed on slides 49, these slides 49 in turn sliding on bars 50 carried by the frames 223, as clearly shown in Figs. 3 and 4. When the mechanism is being operated to insert a staple transversely of the run of the product, the frame 400 slides on the slides 49, these slides 49, when the parts are thus operated being stationary relatively to the frame 23. If now the mechanism be turned so as to insert the staples longitudinally of the run of the product, as shown in Fig. 4, the slides 49 slide on the bars 50 and the upper and lower members 44, 45, of inner frame 400 are stationary relatively to the slides 49. These sliding movements may be given the frame and slides in any suitable manner.

In the particular construction shown the lower frame piece 45 of the inner frame 400 is provided at each end with short racks 51, 52 suitably secured thereto as by bolts 53 and the slides 49 are provided with racks 54, one of which is shown in Figure 3, it being understood that the slide 49 on the opposite side is provided with a similar rack.

These racks are operated through connections which may be somewhat varied. In the particular construction illustrated, referring first to the connection for sliding the frame 400, when the product is being stapled transversely of its run, the racks 51, 52 are engaged with segment gears 56, 57, these gears being fast on a rock shaft 58 extending across the frame 400. One of these segment gears, as the gear 56, has secured thereto or integral therewith, an arm 59 shown in Figure 2, this arm being carried on a hub 60. The arm 59 carries cam arm 61 provided at its lower end with a cam roll 62 which works in the groove of a cam 63 carried on a shaft 37' (see Fig. 3), driven from shaft 31 through suitable

connections not shown. Through this connection the rack and through the rack the frame member 45, is given a reciprocating movement, the parts being timed to cause the forward movement or the movement in the direction of the travel of the product to be at the same speed as that of the product. 70

When the parts are given a 90 degree turn as before described to position them to staple longitudinally of the run of the product, the arm 61 is disconnected from the hub so that the racks 51, 52 are not given any movement. When in this position the reciprocating movement of the stapling mechanism is effected through the slides 49 and racks 54 before referred to. To effect this the racks engage with segment gears 64, 64', one of which is shown in Figure 3, these gears being carried on a rock shaft 65 extending across the machine at an angle to the shaft 58 before referred to and one of these gears, as the gear 64, is shown as provided with an arm 66 secured to or integral therewith, this arm being carried on a hub 67. This arm 66 is connected with an arm 68 shown in full lines in Figure 2, and this arm 68 at its lower end carries a cam roller 69 which runs in the groove of a cam 70 similar to the cam 63 before referred to, and likewise carried on the shaft 37. When the parts are to be operated to effect stapling longitudinally of the run of the product, this arm 68 is connected with the hub 67, and as before stated, the arm 61 is disconnected from the hub 60. With this construction the reciprocating movement can be given the frame 400 in either position of the parts, it being understood that the parts just referred to are timed to give the proper forward speed, which is the speed of the product. 105

In machines embodying the invention in its best form anti-friction devices will be provided for the frame 23 so that the turning movement of the frame as described may be easily and readily effected. While these anti-friction devices may be of various forms, in the particular construction illustrated, the bed or base 22 is formed (see Fig. 4) with a circular web 71 forming a track for anti-friction rolls 72, these rolls 72 being carried in brackets 73 (see Figs. 2 and 3) depending from the lower part of the frame bottom, these rolls being provided in any sufficient number, four such rolls being illustrated. 110

The staple forming and inserting mechanism may be of any usual or desired character, and preferably will be such as to insert a line of staples in the product and a mechanism for inserting two staples in line has been illustrated. As will be understood, this stapling mechanism is carried by the inner carrier frame 400, before referred to, and partakes of the movement of this frame, and the operating mechanism of the stapling 125

devices is the same, no matter what position the parts are in.

In the construction illustrated this staple inserting mechanism is driven from the upper driving face 28 of the miter gear 27 before referred to, through a miter gear 73 (see Fig. 4) mounted on a shaft 74 supported from brackets 75 depending from the lower part of the frame 23. This shaft at its other end carries a miter gear 76 which meshes with a miter gear 77 on a vertical shaft 78 mounted in bearings 79 supported from the frame 23 before referred to, this shaft 78 being the operating shaft for the staple inserting and clinching mechanisms and the registering devices.

While the connections from this shaft for operating these parts may be somewhat varied, such connections will, where the staple inserting mechanism is given a travelling movement with the product, be so constructed as to permit this movement and at the same time remain in driving connection with the shaft 78. In the particular construction illustrated, and referring first to the connections for operating the staple clinching mechanisms there are shown conventionally a pair of anvils 80, 81 (see Fig. 3) arranged to insert two staples in line in the product. These anvils are carried on arms 82 which are operated in the usual manner through cams 83 carried on shafts 84 slidably supported in bearings 84' depending from the upper member 44 of the frame 400 before referred to (see Figs. 3 and 4). These shafts 84 are mounted to partake of the back and forth movement of the frame and at the same time remain in driving connection with the driving shaft 78 before referred to. As shown (see Fig. 4) there is provided a shaft 85 supported in the carrier 23 extending across it, this shaft at one end being provided with a miter gear 86 (see Fig. 4) which engages with a miter gear 87 on the shaft 78. This shaft 85 is provided with a pair of miter gears 86 which are keyed as at 87' to slide on the shaft, this sliding being effected by means of yokes 88 taking in the grooves of collars 89 on the shaft. The yokes 88 are secured in any suitable manner, as by bolts 90, to the upper frame member 44 before referred to. Meshing with the miter gears 86 are miter gears 91 on the shafts 84 before referred to and by which the staple clinching mechanism is operated. With this construction the staple clinching mechanism may be given a to and fro movement to keep up with the product, and when a longitudinal stapling as being effected the connections as just described are employed, the frame 400 and with it the gears 91 being reciprocated through the slides 49 and slide operating segment gears 64 as described.

When transverse stapling is to be effected

and the frames 23, 400 are swung at right angles to the position shown in Fig. 2, the miter gears 86 do not move on the shaft 85, but the frame 400 is reciprocated on the slides 49 by the segment racks 51, 52 before referred to. The driving miter gears 91 are, however, held in driving connection with the miter gears 86.

The same connections are employed for driving the staple forming mechanisms which are diagrammatically illustrated in Figs. 1 and 2 and marked 95, 96. These staple forming mechanisms are of the usual form and are supplied with wire from spools 97 shown in Figure 1 through the usual draw off rollers 97' to the staple forming plungers indicated at 98. The staple forming mechanism is driven as shown in Fig. 3 from a shaft 99 through miters 100, 100', from shaft 78 in the same manner as that described for driving the staple clinching mechanism and a description thereof need not be further repeated.

In machines embodying the invention in its best form, devices will be provided for registering the product in the correct stapling position and while these devices may be of various characters, in the best form they will include means for front and side registering the product in either position of the stapler. These registering devices may be of any suitable character and operate in any desirable manner. In the particular construction illustrated they are operated from the shaft 99 before referred to, which at its outer end beyond the frame 23 is provided with a spur gear 101 which meshes with a spur gear 102 on a controller shaft 103, supported in the side members 225 of the frame 23. As shown there are provided (see Figs. 5 and 6) front registering fingers 105, 106, a pair of side registering fingers 104, 104', and a pair of fingers 107, 108 which act as front registering fingers in one position of the stapling mechanism and as side registering in another position. If the parts are in the transverse stapling position as shown in Fig. 5 and a product is coming in in the direction of arrow α of that figure, the fingers 107, 108 act to front register the product and the fingers 104, 104' act to side-register the product, the fingers 105, 106, being silenced. If now the frame be swung to a position at right angles to the position shown in Fig. 5 to staple a product longitudinally, then the fingers 107, 108 act as side registering stops and the fingers 105, 106 act as front registering stops, the fingers 104, 104' being silenced. The side registering is effected against suitable side stops 180, removably secured on the frame 400 and indicated in dotted lines in Fig. 5, these stops being transferred to an end of the frame when the parts have been turned for longitudinal

stapling. Means are provided for operating these stops to register the sheets, which means may be of any suitable character. One such means is that illustrated in Fig. 6, in which an up and down and a trembling or juggling motion is given the fingers and operating mechanism for the stops 107, 108 is shown. As there illustrated, the fingers, as finger 107, is carried on a bracket 107' pivoted on shaft 109. This shaft has also secured thereto an arm 110 secured at one end to a link 111. This link at its other end is secured to an arm 112 carried on a rock shaft 113. On this rock shaft is an arm 114 which has secured thereto one end of a cam fork 115, this cam fork having a cam roll 116 operating from a cam 117 shown in dotted lines in Fig. 6 and full lines in Fig. 5, this cam being keyed on shaft 103 so as to have a sliding movement therealong. The fingers 104, and 104' are mounted on a short shaft 119 supported in frame 400 and in a similar manner as the fingers 107, 108. This shaft 119 is operated from a cam 120 keyed on the shaft 103 before referred to, through a cam fork 121 having a cam roll 121', this cam fork at its other end being secured (see Fig. 4) to an arm 122 on a rock shaft 113, this rock shaft having an arm 124 secured to a link 125, this link being secured to a lever (see Fig. 5) 126 pivoted on a stud 127, this lever being connected to the shaft 119 carrying the fingers.

Fingers 105, 106 are similarly supported on a shaft 128 supported in frame 400 and operated from a cam 129 on the shaft 103 before referred to through a cam fork 130 having a cam roll 130'. This cam fork at its other end is secured to an arm 131 on a hub 132 rotatable around the shaft 113. The other end of this hub carries an arm 133 which arm is connected to a link similar to the link 125 before referred to, which link is connected to a lever 134, this lever operating the shaft 128 and through it the fingers.

As these fingers and connections for operating them are carried by the frame 400 which as before stated has a reciprocating movement relatively to the frame 23 in either position of the latter, means are provided whereby the fingers may partake of these movements without becoming disconnected from the driving shaft 103. As shown the hubs of the cams 120, 129 have grooved collars 135, and the cam forks 121, 130 take into these grooves. Similarly a grooved collar 136 (see Fig. 5) is provided on the hub of cam 117 into which the cam fork 115 takes. With this construction, when the parts are reciprocated up and down in the position shown in Fig. 5, the forks slide the cams along the shaft 103.

When the parts are turned from the position shown in Fig. 5 and reciprocated, this

movement is allowed by the provision of forks 137 fast on the reciprocating frame 400, one of which is clearly shown in Fig. 4, the lever connections between the cam rolls and the fingers taking up the movement.

From the stapling mechanism the stapled product is, if desired, forwarded by the tapes to a folding mechanism.

This folding mechanism may be of any desired character to produce the final product required. When the product has been stapled longitudinally of its run it is folded by the usual chopper folder indicated in Fig. 1 by the numeral 140 driven by the usual lever and rod construction 141, the folder operating, as is usual, to fold along the longitudinally inserted staples, and the product is led through this folder by the belts or tapes 12, 13 before referred to.

Where the product is to be folded transversely of its run, that is across, the product may be delivered by the tapes to a cross folder shown as a folding cylinder 142 having the usual folding blade 143 co-operating with folding off rolls 144. When this folder is used the chopper folder 140 is silenced as by disconnecting operating rod 141.

The various mechanisms may be driven from the power shaft 39 through any usual gear or other connections, a detailed description of which is unnecessary.

The operation of the mechanism is clear from the above description. It will be understood, however, that when the carrier is swung from one position to another, the belts are uncoupled and the wire disconnected, and after the carrier has been turned the belts are rethreaded through the frames and the wire again adjusted. The side stops where such are used are also readjusted as above described. It is understood of course that the space between the frames is sufficient to permit the widest product which is to be stapled to pass between them.

While the construction and arrangement of the parts, and the mechanism for operating them is a preferred one and a wire stapler has been shown and described, it will be understood that various changes may be made in them and that other mechanisms may be employed for securing the product together without departing from the invention.

What I claim is:

1. The combination with means for forwarding a product, of stapling mechanism, means for positioning the stapling mechanism to insert staples in the product on the fold line either transversely or longitudinally of the run of the product, and means for folding the stapled product.

2. The combination with means for forwarding a product, a stapling mechanism, means for positioning the stapling mecha-

nism to insert staples in the product on the fold line either transversely or longitudinally of the run of the product, and means for folding the product either transversely or longitudinally of its run.

5. The combination with means for forwarding a product, of a stapling mechanism, means for positioning the stapling mechanism to insert a staple either transversely or longitudinally of the run of the product, means for registering the product with respect to the stapling mechanism in either position, and means for folding the product.

15. The combination with means for forwarding a product, of a stapling mechanism, means for positioning the stapling mechanism to insert a staple either transversely or longitudinally of the run of the product, means for registering the product with respect to the stapling mechanism in either position, and means for folding the stapled product either transversely or longitudinally of its run.

25. The combination of a printing couple, means for cutting sheets from a web printed thereby, means for collecting the sheets, means for forwarding the collected product, a stapling mechanism, and means for positioning the stapling mechanism to insert a staple either transversely or longitudinally of the run of the product.

35. The combination of a printing couple, a stapling mechanism, means for forwarding a product from the printing couple to the stapling mechanism, and means for positioning the stapling mechanism to insert a staple in the product either transversely or longitudinally of its run.

45. The combination of a printing couple, means for cutting sheets from a web printed thereby, means for collecting the sheets, means for forwarding the collected product, a stapling mechanism, means for positioning the stapling mechanism to insert a staple either transversely or longitudinally of the run of the product, and means for folding the product.

55. The combination of a printing couple, means for cutting sheets from a web printed thereby, means for collecting the sheets, means for forwarding the collected product, a stapling mechanism, means for positioning the stapling mechanism to insert a staple either transversely or longitudinally of the run of the product, and means for folding the product either transversely or longitudinally of the stapled line.

60. The combination with means for forwarding a product, of a stapling mechanism capacitated to insert a line of staples in the product either transversely or longitudinally of the run of the product, means for registering the product with respect to the stapling mechanism in either position, and

means for folding the product along either 65 stapled line.

10. The combination with means for forwarding a product, of a stapling mechanism capacitated to insert a line of staples in the product either transversely or longitudinally 70 of the run of the product, means for moving the stapling mechanism with the product during the stapling operation, means for registering the product with respect to the stapling mechanism, and means for folding 75 the product either transversely or longitudinally of its run.

11. The combination of a printing couple, a stapling mechanism, means for forwarding a product from the printing couple to 80 the stapling mechanism, means for positioning the stapling mechanism to insert a staple in the product either transversely or longitudinally of its run, and means for folding the stapled product either transversely or 85 longitudinally of its run.

12. The combination of a printing couple, means for forwarding a product therefrom, and a stapling mechanism to which the product is forwarded capacitated to insert a line 90 of staples in the product either transversely or longitudinally of its run.

13. The combination of a printing couple, means for forwarding a product therefrom, a stapling mechanism to which the product is forwarded capacitated to insert a line of 95 staples in the product either transversely or longitudinally of its run, and means for folding the stapled products.

14. The combination of a printing couple, 100 means for forwarding a product therefrom, a stapling mechanism to which the product is forwarded capacitated to insert a line of staples in the product during the movement of the product either transversely or longitudinally of its run.

15. The combination of a printing couple, means for forwarding a product therefrom, a stapling mechanism to which the product is forwarded capacitated to insert a line of 110 staples in the product during the movement of the product either transversely or longitudinally of its run, and means for folding the stapled product.

16. The combination of a printing couple, 115 means for forwarding a product therefrom, a stapling mechanism to which the product is forwarded capacitated to insert a line of staples in the product during the movement of the product either transversely or longitudinally of its run, and means for folding the stapled product, either transversely or longitudinally of its run.

In witness whereof I have hereunto signed my name.

ISABELLA ROESEN.
Executrix of the Estate of Oscar Roesen,
Deceased.
